UNITED STATES PATENT OFFICE.

JOHN J. GRAFFLIN, OF ATLANTA, GEORGIA.

VACUUM-CONTROL APPARATUS.

Application filed August 13, 1921. Serial No. 492,181.

To all whom it may concern:

Be it known that I, JOHN J. GRAFFLIN, a citizen of the United States, and a resident of Atlanta, county of Fulton, State of Georgia, have invented certain new and useful Improvements in Vacuum-Control Apparatus, of which the following is a specification.

My invention relates broadly to systems in which, for one purpose or another, it is desired to normally maintain a vacuum and there may be coupled with this broad purpose the additional feature of the mechanism automatically actuated or set in motion when the vacuum is definitely broken. An example of such a combined system is illustrated in a prior application filed by me on April 25th, 1921, Serial No. 464,280. In said prior application, I have set forth a dry pipe sprinkler system for fire protection and in that instance the vacuum is normally maintained to keep the interior of the sprinkler pipes dry and upon definite breaking of the vacuum as by the opening of a sprinkler head, the mechanism automatically trips a hydraulic valve, which admits the water into the sprinkler pipes. The mechanism shown in the present application is, in some particulars, an improvement on the broad principle illustrated in said prior application and some of these features are claimed broadly in the present case.

The vacuum control apparatus, according to the present invention, comprises, in the first place, any suitable form of vacuum pump for exhausting air from the system to be evacuated, a novel form of check valve through which the exhausted air is removed from the system, a pressure responsive device by which the vacuum pump is thrown into operation to restore the vacuum to normal when variations in the vacuum have occurred, within, what I may term a normal operating range of the system and another pressure responsive device actuated upon definite destruction of the vacuum beyond this normal working range to throw into operation some extraneous mechanism such as, for example, a hydraulic valve, which may be, for instance, the hydraulic valve for admitting water into a dry pipe sprinkler system. Reference will be made to the accompanying drawing to clearly set forth the principles employed and to en-

able those skilled in the art to practice the invention.

In said drawings

Figure 1 represents a diagrammatic view in elevation of apparatus constructed in accordance with my invention. 60

Figures 2 and 3 are detail elevations of parts actuated by the pressure responsive devices referred to.

Figure 4 is a detail plan view showing certain operating connections of the apparatus shown in Figure 2. 65

Figure 5 is a horizontal section on the line 5—5 of Figure 1, and

Figure 6 is a plan view showing the mounting of one of the pressure responsive devices, with a part in section. 70

Referring in detail to said drawing, 10 indicates a vacuum pipe, which may lead into a relatively large chamber 11, from which a vacuum pipe 12 leads through an inclined enlargement 13 containing a body of mercury 14 and a body of water 15. From the chamber 13, a vacuum pipe 16 leads into a vacuum pump 17, which may be actuated by water supplied by pipe 18 under the control of a piston valve 19. Piston valve 19 delivers through the pump 17, which discharges the water and exhausted air through pipe 20, which has a slight upward offset, as indicated at 21, and finally discharges through the outlet 22 into a waste pipe 23. Upon opening the piston valve 19, water passes through the vacuum pump 17 and thus withdraws air through vacuum pipe 10, chamber 11, pipe 12, mercury 14, water 15 and pipe 16. The body of mercury 14, together with the body of water 15, provides a seal or liquid check valve for preventing the return of air through the pipes described. In the operation of exhausting the system, the mercury is drawn into the enlargement forming chamber 13, after which the mercury returns into the position indicated in Figure 1 of the drawings. The passage of air bubbles through the mercury has, in practice, a tendency to carry small drops of mercury out of the system and to prevent this, the body of water 15 is maintained upon the surface of the mercury. This layer of water effectively washes the air of mercury. The upward offset 21 of the pipe 20 performs the function of retaining a small quantity of water in the pipe 20 when the supply is discontinued and this 110

remnant of water automatically drains back into the check valve chamber 13 where it forms the body of water 15 described.

The means for automatically actuating the piston valve 19 will now be described. Leading from the chamber 11 or other evacuated part of the system is a vacuum pipe 24, from which a branch pipe 25 communicates with the top of a mercury reservoir 26. From the bottom of the reservoir 26, a pipe 27 leads downwardly into a mercury well 28, which forms part of a suspended or floating cup 29 open to the atmosphere. The mercury cup 29 is provided with a trunnion ring 30, by which the cup is pivotally supported in the free ends of levers 31 (see Figures 1 and 6). The position of the mercury cup 29 within the trunnion ring 30 is adjustable as to height by loosening the screws 32. The levers 31 are pivoted at 33 upon a journal rod mounted in a U-shaped bracket 34, which is suitably secured on the wall of housing 35. A pair of triangular plates or arms 36 are similarly pivoted on journal rod 33 and are fixed to the levers 31 by cross pins 37. Spacing sleeves 38 and 39 are mounted on the journal 33 and cross pin 37 between the plates 36 to space apart the levers and arms and they may be keyed to the journal rod and cross pin to hold them in place. The lever 31 with the plates 36 constitute a bell crank lever actuated by the mercury cup 29 and its contents, as will be described. In order that the movement of this bell crank lever may be transmitted to open and close the piston valve 19 of the vacuum pump, the free ends or extremities of the plates 36 are connected with a link 40, which has a slot 41 in its upper end, through which slot passes a transverse pin or rod 42, mounted in the extremities of the plates 36. Sleeves 43, keyed on cross pin 42 maintain the upper end of the link 40 in proper position. The lower end of the link 40 is deflected at 40^a and straddles the piston valve 19. It is suitably connected as at 40^b with the piston stem of the valve 19 so that reciprocation of the link opens and closes the valve. The mercury cup 29 is supplied with a body of mercury of suitable quantity and this body of mercury is partly drawn up into the stationary reservoir 26 when the normal vacuum is being maintained within the system. As vacuum decreases, more mercury flows into the well of mercury cup 29 and thus increases the weight or load sustained by the levers 31. This variable weight of mercury is normally counter-balanced by a counter-balance weight 44 mounted between levers 45, which are fulcrumed to the free ends of links 46, journaled at 47 in a U-shaped bracket 48 (see Figure 5). The other ends of the levers 45 are connected as shown in Figure 1 with the ends of pivot pin 42 on

plates 36. With this construction, the actuation of link 40 is dependent upon the opposed relative forces of counter-weight 44 and mercury cup 29. The values of these forces are so proportioned that, during the existence of a vacuum in the system within prescribed normal limits, the force of counter-weight exceeds the gravity effect of the mercury cup 29, by reason of the quantity of mercury withdrawn from cup 29 into the reservoir 26. When the vacuum decreases, the mercury will flow from reservoir 26 into cup 29 to maintain the hydrostatic head of mercury corresponding to the difference between internal and atmospheric pressures. An important feature of the improvement in the present invention resides in the provision of an enlargement of pipe 27 into the form of a reservoir 26 of relatively great transverse area so that the quantity of mercury which is transferred to raise or lower the surface within the reservoir is very great as compared with that corresponding to changes in surface level within the rest of the mercury tube. A similar consideration applies to the enlargement forming the cup 29 above the mercury well 28. By the use of horizontally extended reservoirs 26 and 29, the variation in weight of mercury supported by cup 29 or withdrawn therefrom with a relatively small change in pressure within the evacuated system may be designed to give the desired amount of power for operating the vacuum pump valve 19. In other words, the control may be made very sensitive while gaining ample actuating power for the valve. The lost motion connection between levers 31 and link 40 permits a relatively free movement of the lever downward during the first part of its descent. It will be observed that, as the levers 31 descend, the cup 29 is lowered with respect to the reservoir 26 and, hence, introduces a further withdrawal of mercury from the reservoir 26. In this way, the condition of instability once started by the increase of pressure within the vacuum is built up, as it were, by the initial response to the pressure change. By the time the lost motion of the levers 31 with respect to link 40 has been taken up, the weight of mercury, which has been introduced into the cup 29 has become ample to supply the power required for actuating the valve 19 against the counter-weight 44. The apparatus above described represents what I may term the normal vacuum control and, in practice, is set to turn on the vacuum pump when the vacuum has dropped below the desired normal limit and to shut off the vacuum pump when the normal vacuum has been restored.

The U-tube 50 may be embodied in the apparatus, suitably connected with the pipe 24 and open to atmosphere at its other end so that the mercury column 51 may visually

indicate the vacuum which exists at the time within the system.

An additional feature of importance, which may be incorporated in certain systems, comprises a construction, which may be in general similar to the normal vacuum control mechanism but adapted to actuate some extraneous mechanism upon definite destruction of the vacuum. Such an extraneous mechanism may, for example, be a hydraulic valve for sprinkler systems, such as referred to in my prior application above mentioned. To illustrate this portion of the apparatus, I have shown a hydraulic discharge pipe 60 normally closed by a valve bar 61, pivoted at 62 to the bracket 63, mounted on pipe 64. The valve bar 61 constitutes a hydraulic "trip", which, it may be assumed, permits the extraneous mechanism to come into operation by opening the discharge pipe 60. The outer end of the trip bar 61 is pivoted at 65 with a link 66 provided at its upper end with a latch element such as hook 67. This hook 67, as clearly shown in Figures 1 and 3 of the drawings, may be hung from a roller or sleeve 68 mounted on cross pin 69 between plates 70 similar to the plates 36 above described. The outer ends of the cross pin 69 may be engaged by the ends of counter-balance levers 71 carrying a weight 72 and pivoted against the free ends of links 73 fulcrumed at 74 in a bracket 75. The plates 70 are journalled at 76 in a U-shaped bracket 77 and have secured to them the levers 78, which engage the trunnion ring 79 of a mercury cup 80 into the well 81 of which the mercury pipe 82 from mercury reservoir 83 dips. A vacuum pipe 84 connects reservoir 83 with the evacuated system so that the inner surface of the mercury is exposed to vacuum and the outer surface to atmosphere, as already described in connection with the normal vacuum control. The reservoir 83 in this instance is lower than the reservoir 26 and the cup 80 may have a normal position of stability on the same level with the cup 29. In other words, the difference in elevation between cup 80 and reservoir 83 is less than the difference in elevation between cup 29 and reservoir 26. Thus, with the counter-weight properly designed, this mechanism will remain out of operation so long as the vacuum is maintained within the normal desired range. Upon definite destruction of the vacuum, however, as by the opening of a sprinkler head or other thermostatic valve, the cup 80 will depress the levers 78 into the position shown in dotted lines in Figure 1 and during this operation, the link 66 is unlatched from the roller 68, this action being positively insured by the provision of an abutment stop 85, which may have an anti-friction roller 86 mounted in the lateral

path of the upper end of link 66. When this link is released, the trip bar 61 falls by gravity and water pressure from pipe 60, whereupon the water is discharged from the pipe and the extraneous mechanism is permitted to come into operation.

It is desired to mention particularly that the invention herein shown and described is not to be understood as limited to use in a system such as set forth in my said prior application for patent. In said prior application, the vacuum is maintained within the sprinkler pipes themselves but the vacuum system in the present invention may be separate from the sprinkler pipes or not. In fact, I contemplate, by the present invention, one embodiment in which the vacuum system, such as pipe 10 and chamber 11 are entirely distinct from the water pipes of a sprinkler system but may be employed as a control in buildings having sprinkler systems provided with a main valve, which according to my invention, can, for example, be actuated by the discharge of water from pipe 60. It is equally obvious that the principles of construction and operation herein shown and described may find widely divergent applications entirely apart from the question of fire protection and it will be understood, therefore, that invention is not to be understood as limited to any particular use.

The chamber 11, shown herein, may be regarded as a cushioning device for minimizing the transmission of pulsations from the vacuum pump to the control devices and it may also serve as a reservoir of sufficient capacity to receive and retain water of condensation or leakage during intermediate idle periods when the vacuum pump 19 is not operating. Obviously, water collecting in the reservoir 11 will, upon the next operation of the vacuum pump, be withdrawn through the pipe 12.

I claim;

1. Apparatus responsive to change of pressure comprising in combination a chamber, a liquid reservoir exposed to the pressure within said chamber, a second reservoir exposed to a different pressure from that in the chamber, one of said reservoirs being movable with respect to the other, connecting means whereby said apparatus may be governed by the movement of the movable reservoir and a conduit of relatively small sectional area leading from one of said reservoirs to the other; said reservoirs adapted to contain alternately a quantity of liquid transferable thru said conduit from one to the other upon change of pressure within said chamber, to effect movement of the movable reservoir by gravity.

2. Apparatus responsive to change of vacuum comprising in combination a vacuum chamber, a liquid reservoir exposed

to the vacuum within said chamber, a second reservoir exposed to atmospheric pressure, one of said reservoirs being movable with respect to the other, connecting means whereby said apparatus may be governed by the movement of the movable reservoir and a conduit of relatively small sectional area leading from one of said reservoirs to the other; said reservoirs adapted to contain alternately a quantity of liquid transferable thru said conduit from one to the other upon change of pressure within said chamber, to effect movement of the movable reservoir by gravity.

3. Apparatus responsive to change of vacuum comprising in combination a vacuum chamber, an upper liquid reservoir exposed to the vacuum within said chamber, a lower reservoir exposed to atmosphere, one of said reservoirs being movable with respect to the other, connecting means whereby said apparatus may be governed by the movement of the movable reservoir and a conduit of relatively small sectional area leading from one of said reservoirs to the other; said reservoirs adapted to contain alternately a quantity of liquid transferable thru said conduit from one to the other upon change of vacuum within said chamber, to effect movement of the movable reservoir by gravity.

4. Vacuum governed apparatus comprising in combination a vacuum chamber, a vacuum pump, an upper stationary liquid reservoir in communication with the vacuum

chamber, a lower movable reservoir held in its elevated position by a counter force to stop the pump, connecting means whereby said pump may be governed by the movement of the movable reservoir and a restricted Torricellian connection between the reservoirs, whereby a slight drop in level of the liquid in the upper reservoir will transfer the bulk of the liquid to the lower reservoir and overcome the balancing force so as to start the pump.

5. Apparatus responsive to change of pressure comprising in combination a chamber, a liquid reservoir exposed to the pressure within said chamber, a second reservoir exposed to a different pressure from that in the chamber, one of said reservoirs being movable with respect to the other, connecting means whereby said apparatus may be governed by the movement of the movable reservoir and a conduit of relatively small sectional area leading from one of said reservoirs to the other; said reservoirs adapted to contain alternately a quantity of liquid transferable thru said conduit from one to the other upon change of pressure within said chamber, to effect movement of the movable reservoir by gravity, the said connecting means being provided with lost motion to allow part of the liquid to transfer from one reservoir to the other before meeting the resistance of the apparatus to be moved.

JOHN J. GRAFFLIN.
